UNITED STATES PATENT OFFICE

2,066,682

MECHANISM FOR KNITTING

Alfred Graenz, Philadelphia, Pa., assignor to Non-Run Fabric and Machine Co., Inc., New York, N. Y., a corporation of New York

Application August 5, 1932, Serial No. 627,550

25 Claims.

(Cl. 66—96)

This invention relates to a novel and improved knitting mechanism and to a method which may be practiced thereby. The invention more particularly relates to the inventions described and claimed in my Patents 1,856,053 and 1,862,514, and will be best understood from the following description and the annexed drawings, in which I have shown a selected mechanism by which the method may be practiced. I have also illustrated a fabric which may be made by the method and mechanism described herein.

In the drawings, Fig. 1 is a perspective view of part of a knitting machine having certain parts of my novel mechanism applied thereto.

Fig. 2 is a front view of part of the machine appearing in Fig. 1.

Fig. 3 is a view on a reduced scale approximately on the line 3—3 of Fig. 2, parts being shown in section and other parts being omitted where advisable for the sake of clearness.

Fig. 4 is a view on an enlarged scale taken on a plane substantially the same as the plane of Fig. 3, but omitting a number of the parts appearing in that figure.

Fig. 5 is a view taken approximately on the line 5—5 of Fig. 4.

Fig. 6 is a view taken on the same plane as Fig. 5, but showing the parts in a different position.

Fig. 7 is a view taken on the line 7—7 of Fig. 5.

Fig. 8 is a view taken on the line 8—8 of Fig. 6.

Figs. 9, 10, 11, and 12 are views corresponding to Figs. 5 and 6, but showing the parts in still other positions.

Fig. 13 is a fragmentary view taken on the line 13—13 of Fig. 3, parts being broken away and other parts omitted for the sake of clearness.

Figs. 14, 15, and 16 are views corresponding to Fig. 13, but showing the parts in different positions.

Figs. 17 to 24, inclusive, are diagrammatic views in the form of sections through the sinker head of the machine and associated mechanism and showing successive relative positions of the different parts in knitting a fabric with this invention.

Fig. 25 is a perspective view diagrammatically showing one step in the operation of knitting according to this invention.

Fig. 26 is a view similar to Fig. 25, but showing a succeeding step in the operation.

Fig. 27 is a view similar to Figs. 25 and 26, but showing a step which may be followed instead of that shown in Fig. 26.

Fig. 28 is a diagrammatic showing of a knitted

fabric which may be formed according to this invention.

Fig. 29 is a view on the line 29—29 of Fig. 30, parts being omitted for the sake of clearness.

Fig. 30 is a view taken on the line 30—30 of Fig. 29.

Fig. 31 is a view on the line 31—31 of Fig. 29.

Fig. 32 is a view of a portion of the apparatus appearing in Fig. 29 as seen from the opposite side thereof.

Fig. 33 is a top view of the apparatus appearing in Fig. 32, with certain parts omitted.

Fig. 34 is a view of the apparatus appearing in Fig. 32 as viewed from the left of that figure.

Fig. 35 is a view on the line 35—35 of Fig. 3.

Fig. 36 is a view of the same apparatus as shown in Fig. 35 as seen from the right of that figure.

Fig. 37 is a vertical transverse section through the entire machine showing part of the mechanism for operating the locking points.

Fig. 38 is a view similar to Fig. 37, but showing the mechanism for operating the needle bar and other elements.

Fig. 39 is a perspective fragmentary view showing the loose course motion and the control therefor.

The invention covered by this application relates to a knitted fabric and more particularly to fabric of the so-called "full-fashioned" type well known in the art and used to advantage in the manufacture of hosiery. In my aforesaid Patents 1,856,053 and 1,862,514, I have shown samples of fabric in which the loops or stitches are so arranged as to render the fabric substantially of a non-run character throughout the body thereof.

Fig. 39 is a perspective fragmentary view showing the loose course motion and the control therefor.

30 The invention covered by this application relates to a knitted fabric and more particularly to fabric of the so-called "full-fashioned" type well known in the art and used to advantage in the manufacture of hosiery. In my aforesaid Patents 1,856,053 and 1,862,514, I have shown samples of fabric in which the loops or stitches are so arranged as to render the fabric substantially of a non-run character throughout the body thereof.

35 and I have also shown and described methods and mechanisms for making such a fabric. The mechanism which I shall now describe is readily adapted to make the same general kind of fabric described and illustrated in said patents but by 40 modified mechanism and methods.

The invention may conveniently be practiced on a knitting machine of the well-known Reading type and, for the purpose of convenience, I have illustrated the invention as practiced with such a machine, although, of course, it is to be understood that other types of machines may be used if desired.

One part of the invention relates to novel and improved means for controlling the displacement 50 of selected loops to form the fabric covered in my aforesaid patents, and such means will now be described, particular reference being made to Figs. 1 to 16, inclusive.

In Fig. 28 is shown a section of a fabric, it 55

being understood that this fabric is on a greatly enlarged scale and that the loops therein are shown in conventional form. The fabric comprises courses and wales of loops, course 1, for example, being a regulation plain course, and the courses 2 and 3 together forming a locking zone in which certain selected loops 4 are displaced from the course 2 into the course 3 and into adjacent wales in that course. In this particular instance, every third loop in the course 2 is thus displaced into the course 3. The mechanism about to be described is adapted to select the desired course from which loops are to be displaced and to select the loops in that course 15 which are to be displaced and finally the mechanism can be adjusted so as to select the wale into which the loop is to be displaced.

Referring now particularly to Figs. 1 to 16, inclusive, I have shown therein parts of a machine 20 of the Reading type having rows of needles 5 supported on a needle bar 6, it being understood that the parts shown may be repeated in the assembly so that a number of these parts may be operated from one cam shaft as is usual.

25 Cooperating with the needles 5 are rows of locking points 7, in this instance there being shown one locking point for each four needles, although this relation may be varied as found desirable. These locking points are mounted on bars 8 secured to brackets 9 which, in turn, are secured to a shaft 10 extending longitudinally of the machine and supported from a shaft 11 which, in turn, is carried by a plurality of brackets 12 spaced along the machine, although 35 only one is shown in these drawings.

The bracket 12 is carried by a rock shaft 13. Rocking of the shaft 13 by means to be described later will cause the points 7 to dip downwardly so as to enter selected loops which are to be displaced. The lateral displacement of the points 7 to displace the loops carried by these points into adjacent wales of the fabric may be caused by movement of the shaft 10 parallel to its axis and, according to the present invention, this movement 40 may be caused by means exemplified by the roller 14 engaging a collar 15 on the shaft 10, as best shown in Figs. 4, 7, and 8. This roller 14 is revolvably mounted upon a lever 16 having its upper end pivotally mounted at 17 on the forward 45 ward end of a rock shaft 18.

The shaft 18 is mounted in a bearing 19 carried by a bracket 20 secured to the shaft 13 and in a bearing 21 secured to the shaft 11 so that, upon rocking of the shaft 13, the shaft 18 will also 50 rock forwardly in exact accordance with the dipping motion of the points 7. The shaft 18 is given an oscillating motion by means of a rod 22 having a pin 23 engaging in a slot 24 of an arm 25 rigidly secured to the shaft 18. The means 55 for operating the rod 22 will be more fully described later.

The collar 15 on the shaft 10 is held against the roller 14 by means of a spring 26 shown in Fig. 2, and engagement of these parts is also 60 assured by a light spring 27, also shown in Fig. 2. The normal inoperative positions of the parts are shown in Fig. 2, and when in those positions, the spring 26 is not charged. The movement of the shaft 18 may be considered as being between 65 the positions shown in Figs. 5 and 6, Fig. 5 showing the oscillation of the shaft in a counterclockwise direction, and Fig. 6 showing the oscillation of the same shaft in a clockwise direction. When the lever 16 is in the position shown in Fig. 2, it will be seen that it will rock about the

center of the roller 14, this roller bearing upon the collar 15. This is the normal idle movement of the lever during its inoperative stages, and during such idle movement it will have no effect upon the other mechanism.

Disposed in the lower end of the lever 16 is a roller 28 which, in the idle movement just referred to above, is spaced a sufficient distance from a chamfered surface 29 on a block 30 so this idle movement may take place without the 10 roller engaging the block. This block 30 may conveniently be called a selector and, as best shown in Figs. 13, 14, 15, and 16, has a plurality of surfaces 31, 32, 33, and 34, any one of which may be engaged by the roller 28, the selector 15 being secured to a rod 35 slidably mounted in a bearing 36 upon the frame of the machine. Movement of the rod 35 may bring any one of these surfaces into position where, when the points dip, the roller 28 will pass along one of 20 these surfaces, it being remembered that the lever 16 will move in exact accordance with the dipping movement of the points.

When the roller 28 engages one of the surfaces on the selector, then oscillation of the 25 shaft 18 will cause rocking of the lever 16 about the center of the roller 28, this roller then having a fixed bearing surface with which to contact. If the shaft 18 oscillates in the direction shown in Fig. 5, then the roller 14 tends to move 30 away from the collar 15, thus permitting the spring 26 to move the shaft 10 to the right, and this will move the points 7 to the right, as indicated by the arrows in Figs. 5 and 7. Likewise, when the shaft 18 oscillates in the direction shown in Fig. 6, this will cause the roller 14 to move the collar 15 and, consequently, the shaft 10 to the left, thus causing the points 7 to move to the left, as indicated by the arrows in Figs. 6 and 8. The amount of this movement 35 is indicated by the difference between the full line and dash line positions of the points in Figs. 5 and 6, and is shown as being equal to the spacing between two adjacent needles 5. By adjusting the pin 23 along the slot 24, however, the 40 amount of the movement of the points 7 may be varied as desired.

The surfaces 31, 32, 33, and 34 are shown as inclined to the vertical in Fig. 4, this being for the purpose of providing a path of the proper 50 shape for the roller 28 during the dipping movement of the points 7 and of the shaft 18. The relation of the lever 16 to the roller 14 may be adjusted by the opposing screws 37 best shown in Figs. 7 and 8 so as to accurately adjust the 55 roller 28 with respect to the various surfaces on the selector.

By operation of the selector, as pointed out above, any one of the surfaces thereon may be brought into position at the right time to contact with the roller 28. The parts are so timed that before any dipping operation of the points takes place, the selector is actuated to bring one of its surfaces 31, 32, 33, or 34 into such position that it will be engaged by the roller 28 upon 60 occurrence of the dipping operation. By proper selection and placing of the surfaces on the selector, the initial dipping motion which carries the lever 16 downwardly will cause engagement of the roller 28 with one of the surfaces on the 65 selector before the points 7 come into cooperative relation to the needles 5. As the roller 28 thus engages one of the surfaces on the selector, the shaft 10 will be given a motion lengthwise of its axis, depending upon the particular selector sur- 70 75

face which is engaged. In the illustrated embodiment, I have shown these surfaces so arranged that this initial movement of the shaft will displace the points an amount equal to 1, 2, 3, or 4 needle spacings. For example, in Fig. 9 I have shown the roller 28 as engaging the surface 31 which causes an initial shift of the shaft 10 an amount equal to the spacing of two adjacent needles or an amount which may be termed one needle spacing. In Fig. 10, on the other hand, the selector has been shifted to a position where the roller 28 engages the surface 32, thus shifting the points 7 two needle spacings, while in Figs. 11 and 12, by shifting the selector so that the roller will engage the surfaces 33 and 34, respectively, the points are shifted three and four needle spacings, respectively. In Figs. 9, 10, 11, and 12, the points are shown in cooperative relation to the needles, but it is to be understood that the initial shifting of the points takes place before the points are dipped into the loops on the needles.

The positions of the roller 28 and selector 30 shown in Figs. 9, 10, 11, and 12 correspond to the positions of the same parts appearing in Figs. 13, 14, 15, and 16, respectively. The selector is moved forwardly at the proper time by means of a roller 38 engaging the front of the same and mounted upon a lever 39 rocked by means which will be described later. The selector is moved by the roller 38 towards the right in Figs. 3 and 4, and then as the lever 39 rocks to the left in these figures, the selector may also move to the left, this movement being limited by engagement of a stop 39' with the bearing 36 and the movement being caused by a spring 38'. When this stop engages the bearing, the parts are in the positions shown in Figs. 9 and 13 wherein the roller 28 will engage the surface 31 of the selector. If it is desired to have the roller engage one of the other surfaces, then some other means is used to stop the movement of the selector towards the left, this means being exemplified by a stop 40 pivoted to a bracket 41 which is secured to the shaft 35. This stop is shown as being limited in its downward movement by a pin 42 (Fig. 4) and freely rotatable in a clockwise direction so that it may be put out of operation if desired or so that it may move upwardly a smaller amount during the operation now to be described.

Mounted on the frame of the machine are a plurality of dogs 43, 44, and 45 which have their forward ends normally disposed below the stop 40 as indicated in Fig. 1. By a control means to be described later, these dogs may be raised into position where one of them will engage either one of the steps 46, 47, or 48 on the stop 40 and thus determine the amount of movement of the selector to the left. For example, when no one of the dogs is thus raised, the selector will return to the position shown in Fig. 13, its movement being limited by the stop 39', whereas operation of one of the dogs 43, 44, or 45 will result in engagement thereof with the steps 46, 47, and 48, respectively, and the parts will occupy the position shown in Figs. 14, 15, and 16, respectively.

A brief summary of the operation of the parts thus far described will now be given, and in this connection I will refer not only to Figs. 1 to 16, inclusive, and to Fig. 28, but will also refer somewhat specifically to Figs. 17 to 27, inclusive.

Assume that the fabric has been knitted to the state appearing in Fig. 25, wherein appears a

plain course of loops 49 followed by two courses 50 and 51, which together form a locking zone, certain loops 52 being displaced from the course 50 into the course 51 and into adjacent wales in that course. We may also assume that another course 53 of plain loops has been formed and that a second locking zone is about to be formed. At this stage, a course of loops 54 has been formed, certain of which, however, are to be later displaced into a succeeding course to aid in forming a locking zone, all in a manner more fully described in my aforesaid prior patents. The thread 55 in the succeeding course is disposed within spring beards 56 of the needles 5 and is about to be pulled through the loops 54. For the sake of convenience, I have shown the locking points 7 as being provided at every fourth needle, and in Fig. 25 these points are about to enter selected ones of the loops 54, these loops being designated 54'. The initial position of the points 7 before being brought into the position shown in Fig. 25, is indicated in Fig. 17, Fig. 18 showing the positions of the point, needle, and thread corresponding to Fig. 25. While the points are in the approximate position shown in Fig. 17, they will be given the lateral movement determined by the selector 30, the selector at this point being moved into position so that when the points dip, they will be shifted generally parallel to the row of needles, thereby selecting the loops 54' in the course 54 which are to be displaced. By the time the points reach the position indicated in Fig. 18, such shifting has been substantially completed.

It will, of course, be assumed that the fabric, as usual, is being moved to the right as viewed in Figs. 17 to 24, inclusive, and that the usual sinkers, dividers, and knocking-over bits are employed. These parts are shown in these figures but will not be further mentioned, as their operation is well understood in the art.

While the needles 5 are operating to pull the thread 55 through the loops in the course 54, the points 7 will now operate to displace the loops 54' in the manner described in my aforesaid patents. In Fig. 19, the needle with the thread 55 within its beard has moved into engagement with the points 7, and then the parts move downwardly together to the position shown in Fig. 20, wherein the points 7 pass through the loops 54'. The needle now moves away to the right as shown in Fig. 21, and the fabric moving with it serves to elongate the loops 54', because the points 7 will remain relatively stationary and in engagement with the loops. The points 7 are now given a movement either to the right or to the left, this movement being caused by oscillation of the shaft 18. If the loops 54' are to be displaced to the right as in Fig. 26, then the displacement is caused by the movement indicated in Fig. 5, whereas if they are to be displaced to the left as in Fig. 27, then the movement occurs as shown in Fig. 6. The amount of displacement in either case is shown as corresponding to one wale, but, as pointed out above, by proper adjustment of the pin 23, this displacement may be more if desired. The relative positions of the parts after displacement are indicated in Fig. 23, whereas in Fig. 24 they have returned to their initial position corresponding to that shown in Fig. 17.

It will thus be seen that means is provided for selecting the particular loops in any course which are to be displaced, this being done by the selector 30. Then the loops may be displaced, usually

one wale, either to the right or to the left. In Fig. 28, I have shown the loops 4 as being displaced to the right from the course 2 into the course 3 and then I have shown that certain loops 5 57 may be displaced from the course 3 to the right into the course 58 and into adjacent wales in that course. Similarly, selected loops 59 may be displaced from the course 58 to the right into the course 60. Thus it will be seen that in three 10 successive courses loops have been displaced in one direction, thus forming a distinctive pattern and also insuring that there shall be in each wale sufficient displaced loops to prevent the formation of runs. Incidentally, in Fig. 28 I have 15 shown every third loop as being displaced in stead of every fourth as in Figs. 25, 26, and 27, but, of course, it is to be understood that this is a matter of selection.

Referring again to Fig. 28, it will be seen that 20 the course 60 is followed by a course 61 forming with the course 62 of plain loops a locking zone, here again the displaced loops being moved to the right. The same may be repeated in the next two courses 63 and 64, thus forming a pattern 25 which is distinctive from the pattern shown nearer the bottom of this same figure. Similarly, the courses 65 and 66 and the courses 67 and 68 may be used to form locking zones in which displaced loops are moved to the left instead of to 30 the right.

The showing in Fig. 28 is, of course, intended merely as illustrative, and those skilled in the art will readily see how the pattern may be varied between wide limits.

35 In knitting a fabric where it is desired that it shall be of non-run character substantially throughout its extent, it has been found advantageous to displace the loops in some locking zones to the right and to displace those in other locking zones to the left. It has been found 40 that this makes a more elastic fabric which is less apt to break, because if loops are displaced in one direction, they decrease the elasticity of the fabric in a direction normal to the direction 45 in which they extend. By displacing some loops to the right and some to the left, for example, by alternately displacing loops to the right for a short length of fabric and then to the left for another short length and repeating the arrangement, a fabric is provided which will be of uniform elasticity in both directions.

I have also found that the elasticity of the fabric is increased by forming the course of loops, from which loops are displaced, with a loose 55 course motion, thus providing additional thread and avoiding stretching of the thread by the displacing of the selected loops. The loose course motion in itself is well known in the art, but I believe it to be novel to use the same for the 60 purpose of providing additional thread for displaced loops, particularly in order to provide a non-run fabric. The loose course motion is indicated in Fig. 39 and will be more particularly referred to later.

65 I will now describe the means for controlling the various steps previously described and also the operating mechanism therefor. In doing so, I shall refer particularly to Figs. 1, 3, and 29 to 38, inclusive.

70 The various operations may be conveniently controlled by a pattern chain 69 mounted near the front of the machine above the usual hand-wheel shaft, which shaft has, however, been omitted from these drawings. This chain extends forwardly and rearwardly of the machine

over a sprocket wheel 70 and over idlers 71 and 72, the idler 72 having a spring 73 connected thereto to provide the desired tension on the chain. The chain may control the dogs 43, 44, and 45 which are pivotally mounted at 74 and 5 75 have projections 75 disposed in positions to be engaged by buttons upon the chain. As plainly shown, particularly in Figs. 30 and 34, there is a line of buttons adapted to lift each one of the dogs, the buttons 76 being adapted to actuate the 10 dog 43, while the buttons 77 and 78 are adapted to actuate the dogs 44 and 45, respectively. Each dog will be lifted sufficiently so that its end will come into position to engage one of the steps on the stop 40 in the manner described above, 15 when the particular dog is actuated by one of the buttons. The same movement used to actuate the selector 30 may conveniently be used for actuating the chain, and this arrangement is best shown in Fig. 3 wherein it will be seen 20 that the lever 39 has an arm 79 connected thereto, the end of which is provided with a pawl 80 cooperating with a ratchet 81 upon the shaft 82 which carries the sprocket wheel 70. This pawl is held in engagement with the ratchet by 25 means of a spring 83.

The same chain 69 may conveniently be used to control the means for causing the points 7 to dip and also to control the means which determines whether or not the displaced loops shall 30 be moved to the right or to the left in a locking zone. For this purpose I assume the chain is provided with three other lines of buttons, herein designated 84, 85, and 86. These buttons are so arranged as to operate dogs 87, 88, 35 and 89, respectively, these dogs being pivotally mounted at 90 upon the frame of the machine and each having a projection 91 adapted to be engaged by one of the buttons and thus actuate the dog upon which the projection is secured. 40

The machine is provided with the usual main cam shaft 92 which, as shown in Fig. 37, carries the cam 93 for causing what I have termed the dipping operation of the points 7. As pointed out in my aforesaid patents, this cam operates 45 the points through a roller 94 connected to the points by a link 95 connected to the arm 96 upon which the roller 94 is mounted. As also pointed out in those patents, the roller is maintained in an inoperative position by engagement of a pin 97 upon the arm 96 with a latch 98 secured 50 on a rock shaft 99 to which is also secured an arm 100, upon the end of which is a roller 101 adapted to engage a cam 102 upon the cam shaft.

As explained in my aforesaid patents, the roller 55 101 may be shifted on or off the cam 102. When it is on said cam, the arm 100 will be lifted to move the latch out of engagement with the pin 97 and thus permit the cam 93 to operate the points 7. The shifting may conveniently be accomplished by means of a forked lever 103 pivoted at 104 on the arm 100 and connected to a rod 105 extending lengthwise of the machine. According to my invention, this rod, as best shown in Figs. 1 and 35, is connected to an arm 106 of a bell crank 60 lever mounted upon a vertical pivot 107, the other arm 108 being connected to a rod 109 extending forwardly and terminating in a handle 110. This rod is provided with two recesses 111 and 112, either one of which is adapted to receive a pin 71 connected to one of the dogs 87 or 88, the pin on the dog 87 being best shown in Fig. 30 at 113 and that on the dog 88 being shown at 114. When the rod 109 is pushed rearwardly until the recess 112 75 may receive one of the pins 113 or 114, the rod 105

will be actuated to move the roller 101 entirely out of engagement with the cam 102 and so far out of engagement therewith that operation of the other parts of the mechanism will not bring it into position to be engaged thereby. When, however, the rod 109 is pulled forwardly so that the recess 111 receives one of the pins 113 or 114, then the roller 101, while still out of engagement with the cam 102, is in such position relative thereto that a slight forward movement of the rod 109 will operate the rod 105 to bring the roller 101 into engagement with the cam 102 and thus cause operation of the points 7. Such movement of the rod 109 may be effected by either one of the dogs 87 or 88, these two dogs operating in identically the same manner except that they are operated by different lines of buttons and thus may be used to form different patterns. The device is essentially one for selecting courses from which loops are to be displaced by the points 7 and so the buttons in the line operating the dog 87 may be so spaced as to cause the points to operate in, say, every second course, whereas the buttons operating the dog 88 may be so arranged as to cause the points to operate in every third course. These are given merely as examples, of course, and, in fact, the buttons in any one line may be changed to give a varied pattern and when it is desired to change from one pattern to another, the rod 109 may be shifted from the pin 113 to the pin 114, or vice versa.

The dog 89 is used to determine whether or not the loop which is to be displaced is moved to the right or to the left of the wale in which it originates, and this may be done by connecting this dog to a rod 115 which extends to the rear of the machine and is connected to an arm 116 of a bell crank lever likewise mounted on the vertical pivot 107 and having another arm 117 connected by a rod 118 to an arm 119 secured to a rock shaft 120 to which is likewise secured an arm 121 having a fork 122 engaging a roller 123 disposed adjacent the double cam on the shaft 92. The roller 123 is mounted on an arm 124 secured to a rock shaft 125 to which is also secured an arm 126, to the rear end of which is pivotally secured the rod 22, so that upon rocking of the arm 124 the rod 22 and consequently the rock shaft 18 may be operated.

The spring 127 (Fig. 36) operates to force the roller 123 towards the cam shaft 92 and into engagement with the double cam thereon. This double cam is best shown in Figs. 3 and 35 and comprises a low cam 128 and a high cam 129, into engagement with one of which the roller 123 may be brought. When the roller 123 is in engagement with the low cam 128, the rod 22 will be pulled downwardly by the spring 127 and thus cause the shaft 18 to operate to give the movement indicated in Fig. 5, causing the points 7 to displace loops to the right; whereas when the same roller 123 engages the cam 129, the rod 22 will be lifted by the action of that cam and thus will cause the shaft 18 to operate to give the movement indicated in Fig. 6, causing the points 7 to displace loops to the left. Thus it will be seen that the dog 89, controlled by the line of buttons 86 on the chain 69, will decide whether or not the loops are to be displaced to the right or to the left.

The selector 30 is reciprocated by movement of the lever 39, as stated above, and this lever may be actuated by means of a link 130 (Figs. 1 and 3) pivoted at 131 to an arm 132 secured to a rock

shaft 133 to which is also secured an arm 134 carrying a roller 135 engaging a cam 136 on the cam shaft 92.

The cam 136 operates continuously to actuate the selector 30 during the formation of each course in the fabric. Ordinarily, when plain knitting is being done and no loops are to be displaced, the movement of the selector will be an idle one and, as pointed out above, the rocking of the lever 16 will have no effect on the points 7, because the roller 28 will then be out of engagement with the selector. When, however, one of the dogs 87 or 88 is operated by one of the buttons on the chain 69, then the point operating mechanism in Fig. 37 is brought into operation and the points, of course, dip. As pointed out above, in an initial stage of the dipping, the points will be laterally shifted, depending upon the operation of the selector, after which the selected loops will be displaced.

In Fig. 38 I have shown the apparatus for operating the needle bar, sinkers, and dividers. No detailed description of this apparatus will be given, because it is of the type generally used in this kind of a machine, suitable changes being made in the configuration of the cams to cause them to operate in proper timed relation with the cams operating the locking points. I may say briefly, however, that the shaft 92 carries the cams 137 and 138 which act, respectively, on rollers 139 and 140 to operate the catch bar motion which controls the operation of the sinkers and dividers, movement being transmitted to those members from the roller 139 by means of elements 141, 142, and 143 and from the roller 140 by means of elements 144, 145, and 146 as is well known in the art. The motion of the needle bar 6 is transmitted thereto by the roller 147 contacting with the cam 148 and operating the elements 149 and 150, and by the roller 151 contacting with the cam 152 and operating the elements 153 and 154.

As mentioned above, I have found that the elasticity of the fabric may be readily increased by forming the loops in the course from which selected loops are to be displaced with the loose course motion, so that there is sufficient thread in the loops to permit displacement of selected loops without substantial stretching of the thread. In Figs. 38 and 39 I have shown a conventional form of loose course motion which may readily be used for this purpose and which comprises an arm 155 mounted on a rock shaft 156 and having a pin 157 adapted to contact with the lower end of the lever 158 which carries the roller 151 operating the needle bar through the other elements 153 and 154. The element 153 is mounted on a pivot 158 carried by the lever 159, and therefore, when the shaft 156 is rocked in such a direction that the pin 157 hits the lever 159 of the arm 149, the roller 151 is pulled away from the cam 152 which it engages, and by the same motion the element 153 is pulled towards the front of the machine and the needle bar is rocked so that the needles 5 are moved towards the back of the machine.

The result of the above motion is to give an additional length to loops which, at a certain stage of the operation, are engaging the needles 5. I time this movement of the needles so that it occurs before the points enter the selected loops which are to be displaced, that is, before the points have reached the position shown in Fig. 20 and preferably when the parts are in the approximate position shown in Fig. 18. The timing of the movement may be accomplished by the usual means comprising a chain 159 carrying but-

tons 160 adapted to operate a projection on a dog 161 connected to a rod 162 which, in turn, is connected to a lever 163 adapted to throw a cam roller 164 into engagement with a cam 165 on the cam shaft 92. The timing could be effected from the chain 69 if desired, but since the loose course motion is a part of standard equipment on machines of this type, I prefer to employ it, making the necessary changes in the buttons to get 10 the required timing.

I have omitted any showing of the usual thread carriers which, as is well known in the art, travel back and forth lengthwise of the needle bars to lay the thread, the movement being achieved by 15 the well-known Coulier motion. It is to be understood that such apparatus is employed, but as its showing would add nothing to the understanding of my invention, I have omitted it from the drawings. Likewise, as pointed out above, I 20 have limited the illustration to the operation of one needle bar, although it is to be understood that for ordinary practice a group of bars will be operated from one cam shaft in the usual way.

The resulting fabric may take the form shown 25 in Fig. 28 or any other desired pattern and, in fact, may take a pattern similar to that shown in my copending application Ser. No. 607,027, now Patent No. 2,023,882. The arrangement described above for knitting such a fabric is one which is 30 more flexible than the one described in my aforesaid patents, as will be readily understood by those skilled in the art. The reason for this flexibility will therefore not be dwelled upon in detail.

The machine illustrated is of the type particularly adapted to make full-fashioned hosiery, and the features described and claimed herein find particular utility in the knitting of hosiery. In Fig. 2 are indicated the usual narrowing points 166 used in fashioning a stocking, and these 40 points may be operated by the usual means well known in the art and which it is not necessary to illustrate or describe.

I claim:

1. In a knitting machine, a row of needles, 45 means cooperating with said needles to form successive courses and wales of loops, a row of locking points adapted to cooperate with said needles to engage loops thereon and to displace them therefrom, means to move said points lengthwise of said needles to engage loops thereon, means arranged to be actuated by said movement to shift said points parallel to said row of needles to select the loops with which the points are to engage, and means to move said points 50 after engagement with said selected loops into adjacent wales.

2. In a knitting machine, a row of needles, means cooperating with said needles to form successive courses and wales of loops, a row of locking points adapted to cooperate with said needles to engage loops thereon and to displace them therefrom, means to move said points lengthwise of said needles to engage loops thereon, means arranged to be actuated by said movement to shift said points parallel to said row of needles to select the loops with which the points are to engage, and means to move said points 60 after engagement with said selected loops into adjacent wales and into adjacent courses.

3. In a knitting machine, a row of needles, 70 means cooperating with said needles to form successive courses and wales of loops, a row of locking points adapted to cooperate with said needles to engage loops thereon and to displace them therefrom, means to move said points lengthwise 75

of said needles to engage loops thereon, means arranged to be actuated by said movement to shift said points parallel to said row of needles to select the loops with which the points are to engage, and means rendered operative by said movement to move said points after engagement with said selected loops into adjacent wales.

4. In a knitting machine, a row of needles, means cooperating with said needles to form successive courses and wales of loops, a row of locking points adapted to cooperate with said needles to engage loops thereon and to displace them therefrom, means to move said points lengthwise of said needles to engage loops thereon, means arranged to be actuated by said movement to shift said points parallel to said row of needles to select the loops with which the points are to engage, and means rendered operative by said movement to move said points after engagement with said selected loops into adjacent wales and 20 into adjacent courses.

5. In a knitting machine, a row of needles, means cooperating with said needles to form successive courses and wales of loops, a row of locking points adapted to cooperate with said needles to engage loops thereon and to displace them therefrom, means to move said points lengthwise of said needles to engage loops thereon, means arranged to be actuated by said movement to shift said points parallel to said row of needles to select the loops with which the points are to engage, means to move said points after engagement with said selected loops into adjacent wales, and means to vary the amount of said last-named movement of the points.

6. In a knitting machine, a row of needles, means cooperating with said needles to form successive courses and wales of loops, a row of locking points adapted to cooperate with said needles to engage loops thereon and to displace them 40 lengthwise of said needles to engage loops thereon, means arranged to be actuated by said movement to shift said points parallel to said row of needles to select the loops with which the points are to engage, means to move said points after engagement with said selected loops into adjacent wales and into adjacent courses, and means to vary the amount of said last-named movement of the points.

7. In a knitting machine, a row of needles, means cooperating with said needles to form successive courses and wales of loops, a row of locking points adapted to cooperate with said needles to engage loops thereon and to displace them 55 lengthwise of said needles to engage loops thereon, means arranged to be actuated by said movement to shift said points parallel to said row of needles to select the loops with which the points are to engage, means likewise actuated by said movement to move said points after engagement with said selected loops into adjacent wales, and means to vary the amount of said last-named movement of the points.

8. In a knitting machine, a row of needles, means cooperating with said needles to form successive courses and wales of loops, a row of locking points adapted to cooperate with said 70 needles to engage loops thereon and to displace them therefrom, means to move said points lengthwise of said needles to engage loops thereon, a movable member adapted to move said points after engagement with said loops to dis- 75

place the loops into adjacent wales, said member normally being inoperative, a second member normally out of engagement with said first member but adapted to be brought into engagement therewith to render said first member operative, means to bring said second member into and out of engagement with said first member, and means to actuate said first member.

9. In a knitting machine, a row of needles, means cooperating with said needles to form successive courses and wales of loops, a row of locking points adapted to cooperate with said needles to engage loops thereon and to displace them therefrom, means to move said points lengthwise of said needles to engage loops thereon, a movable member adapted to move said points after engagement with said loops to displace the loops into adjacent wales, said member normally being inoperative, a second member normally out of engagement with said first member but adapted to be brought into engagement therewith to render said first member operative, means to bring said second member into and out of engagement with said first member, means to actuate said first member, and an automatic control for said last-named means.

10. In a knitting machine, a row of needles, means cooperating with said needles to form successive courses and wales of loops, a row of locking points adapted to cooperate with said needles to engage loops thereon and to displace them therefrom, means to move said points lengthwise of said needles to engage loops thereon, a movable member adapted to move said points after engagement with said loops to displace the loops into adjacent wales, said member normally being inoperative, a second member normally out of engagement with said first member but adapted to be brought into engagement therewith to render said first member operative, means to bring said second member into and out of engagement with said first member, and means to actuate said first member, said members having a plurality of different engaging surfaces, thereby limiting the movement of said first member.

11. In a knitting machine, a row of needles, means cooperating with said needles to form successive courses and wales of loops, a row of locking points adapted to cooperate with said needles to engage loops thereon and to displace them therefrom, means to move said points lengthwise of said needles to engage loops thereon, a movable member adapted to move said points after engagement with said loops to displace the loops into adjacent wales, said member normally being inoperative, a second member normally out of engagement with said first member but adapted to be brought into engagement therewith to render said first member operative, means to bring said second member into and out of engagement with said first member, and means to actuate said first member, said members having a plurality of different engaging surfaces, thereby limiting the movement of said first member, and means for automatically determining the surfaces which are to engage with each other.

12. In a knitting machine, a row of needles having means cooperating therewith to form successive courses and wales of loops, a row of locking points adapted to cooperate with said needles to displace loops therefrom, a rock shaft supporting said locking points, means to rock said shaft to move the points generally length-

wise of said needles to engage loops thereon, a second shaft rotatably mounted on said rock shaft, means for at least partially rotating said second shaft, and means actuated by said rotation to move said locking points generally parallel to said row of needles. 5

13. In a knitting machine, a row of needles having means cooperating therewith to form successive courses and wales of loops, a row of locking points adapted to cooperate with said needles to displace loops therefrom, a rock shaft supporting said locking points, means to rock said shaft to move the points generally lengthwise of said needles to engage loops thereon, a second shaft rotatably mounted on said rock shaft 15, means for at least partially rotating said second shaft, means actuated by said rotation to move said locking points generally parallel to said row of needles, and means to vary the amount of said rotation to change the amount of 20 movement of said points parallel to said row of needles.

14. In a knitting machine, a row of needles having means cooperating therewith to form successive courses and wales of loops, a row of locking points adapted to cooperate with said needles to displace loops therefrom, a rock shaft supporting said locking points, means to rock said shaft to move the points generally lengthwise of said needles to engage loops thereon, a second shaft rotatably mounted on said rock shaft, means for at least partially rotating said second shaft, and means actuated by said rotation to move said locking points generally parallel to said row of needles to the right or to the 35 left of the machine.

15. In a knitting machine, a row of needles having means cooperating therewith to form successive courses and wales of loops, a row of locking points adapted to cooperate with said needles to displace loops therefrom, a rock shaft supporting said locking points, means to rock said shaft to move the points generally lengthwise of said needles to engage loops thereon, a second shaft rotatably mounted on said rock shaft, means for 40 at least partially rotating said second shaft, means adapted to be actuated by said rotation to move said locking points generally parallel to said row of needles, and means actuated by said rotation to move said locking points parallel to said row of needles before their movement by rotation of said second shaft. 45

16. In a knitting machine, a row of needles having means cooperating therewith to form successive courses and wales of loops, a row of locking points adapted to cooperate with said needles to displace loops therefrom, a rock shaft supporting said locking points, means to rock said shaft to move the points generally lengthwise of 50 said needles to engage loops thereon, a second shaft rotatably mounted on said rock shaft, means for at least partially rotating said second shaft, means actuated by said rotation to move said locking points generally parallel to said row of needles before their movement by rotation of said second shaft, a selector to vary the amount of said last-named movement, and means automatically controlling the operation of said selector. 55

17. In a knitting machine, a row of needles having means cooperating therewith to form successive courses and wales of loops, a row of lock- 75

- ing points adapted to cooperate with said needles to displace loops therefrom, a rock shaft supporting said locking points, means to rock said shaft to move the points generally lengthwise of said needles to engage loops thereon, a second shaft rotatably mounted on said rock shaft, means for oscillating said second shaft, said oscillation being idle when plain courses of loops are being formed, and means to render said oscillation active to move said points parallel to said row of needles.
18. In a knitting machine, a row of needles having means cooperating therewith to form successive courses and wales of loops, a row of locking points adapted to cooperate with said needles to displace loops therefrom, a rock shaft supporting said locking points, means to rock said shaft to move the points generally lengthwise of said needles to engage loops thereon, a second shaft rotatably mounted on said rock shaft, means for oscillating said second shaft, said oscillation being idle when plain courses of loops are being formed, means operated by oscillation of said shaft in one direction to move the points in one direction parallel to said row of needles, and means operated by oscillation of said shaft in the opposite direction to move said points in the opposite direction parallel to said row of needles.
19. In a knitting machine, a row of needles having means cooperating therewith to form successive courses and wales of loops, a row of locking points adapted to cooperate with said needles to displace loops therefrom, a rock shaft supporting said locking points, means to rock said shaft to move the points generally lengthwise of said needles to engage loops thereon, a second shaft rotatably mounted on said rock shaft, means for oscillating said second shaft, said oscillation being idle when plain courses of loops are being formed, means operated by oscillation of said shaft in one direction to move the points in one direction parallel to said row of needles, means operated by oscillation of said shaft in the opposite direction to move said points in the opposite direction parallel to said row of needles, and means to automatically determine the direction of movement of said points.
20. In a knitting machine, a row of needles having means cooperating therewith to form successive courses and wales of loops, a row of locking points adapted to cooperate with said needles to displace loops therefrom, a rock shaft supporting said locking points, means to rock said shaft to move the points generally lengthwise of said needles to engage loops thereon, a second shaft rotatably mounted on said rock shaft, means for oscillating said second shaft, said oscillation being idle when plain courses of loops are being formed, means adapted to be operated by oscillation of said shaft in one direction to move the points in one direction parallel to said row of needles, means operated by oscillation of said shaft in the opposite direction to move said points in the opposite direction parallel to said row of needles, and means to shift said locking points parallel to said row of needles before their movement by said oscillation.
21. In a knitting machine, a row of needles having means cooperating therewith to form successive courses and wales of loops, a row of locking points adapted to cooperate with said needles to displace loops therefrom, a rock shaft supporting said locking points, means to rock said shaft to move the points generally lengthwise of said needles to engage loops thereon, a second shaft rotatably mounted on said rock shaft, means for oscillating said second shaft, said oscillation being idle when plain courses of loops are being formed, means operated by oscillation of said shaft in one direction to move the points in one direction parallel to said row of needles, means operated by oscillation of said shaft in the opposite direction to move said points in the opposite direction parallel to said row of needles, and means to shift said locking points parallel to said row of needles before their movement by said oscillation.
22. In a knitting machine, a row of needles having means cooperating therewith to form successive courses and wales of loops, a row of locking points adapted to cooperate with said needles to displace loops therefrom, a rock shaft supporting said locking points, means to rock said shaft to move the points generally lengthwise of said needles to engage loops thereon, a second shaft rotatably mounted on said rock shaft, means for at least partially rotating said second shaft, a lever rocked by oscillation of said shaft, a rod secured to said locking points and disposed adjacent said lever parallel to its rocking movement, and cooperating elements on said lever and rod, whereby rocking of the lever may cause movement of the rod longitudinally thereof.
23. In a knitting machine, a row of needles having means cooperating therewith to form successive courses and wales of loops, a row of locking points adapted to cooperate with said needles to displace loops therefrom, a rock shaft supporting said locking points, means to rock said shaft to move the points generally lengthwise of said needles to engage loops thereon, a second shaft rotatably mounted on said rock shaft, means for at least partially rotating said second shaft, a lever rocked by oscillation of said shaft, a rod secured to said locking points and disposed adjacent said lever parallel to its rocking movement, cooperating elements on said lever and rod, whereby by rocking of the lever may cause movement of the rod longitudinally thereof, a selector forming a fulcrum for said lever, and means to move said selector into and out of engagement with the lever to render the lever operative or inoperative.
24. In a knitting machine, a row of needles having means cooperating therewith to form successive courses and wales of loops, a row of locking points adapted to cooperate with said needles to displace loops therefrom, a rock shaft supporting said locking points, means to rock said shaft to move the points generally lengthwise of said needles to engage loops thereon, a second shaft rotatably mounted on said rock shaft, means for at least partially rotating said second shaft, a lever rocked by oscillation of said shaft, a rod secured to said locking points and disposed adjacent said lever parallel to its rocking movement, operating elements on said lever and rod, whereby rocking of the lever may cause movement of the rod longitudinally thereof, a selector forming a fulcrum for said lever, and means to move said selector into and out of engagement with the lever to render the lever operative or inoperative, said selector having a plurality of surfaces, any one of which may engage said lever to form a fulcrum therefor, whereby the amount of movement of the lever may be varied.
25. In a knitting machine, a row of needles having means cooperating therewith to form successive courses and wales of loops, a row of locking points adapted to cooperate with said needles to displace loops therefrom, a rock shaft supporting said locking points, means to rock said shaft to move the points generally lengthwise of said needles to engage loops thereon, a second shaft rotatably mounted on said rock shaft, means for at least partially rotating said second shaft, a lever rocked by oscillation of said shaft, a rod secured to said locking points and disposed adjacent said lever parallel to its rocking movement, operating elements on said lever and rod, whereby by rocking of the lever may cause movement of the rod longitudinally thereof, a selector forming a fulcrum for said lever, means to rock said rock shaft to bring said locking points into engagement with selected loops, means to move said selector into engagement with said lever, and a common control member for both of said movements.
26. In a knitting machine, a row of needles having means cooperating therewith to form suc-

cessive courses and wales of loops, a row of locking points adapted to cooperate with said needles to displace loops therefrom, a rock shaft supporting said locking points, means to rock said shaft to move the points generally lengthwise of said needles to engage loops thereon, a second shaft rotatably mounted on said rock shaft, means for at least partially rotating said second shaft, a lever rocked by oscillation of said shaft, a rod secured to said locking points and disposed adjacent said lever parallel to its rocking movement, cooperating elements on said lever and rod,

whereby rocking of the lever may cause movement of the rod longitudinally thereof, a selector forming a fulcrum for said lever, means to rock said rock shaft to bring said locking points into engagement with selected loops, means to move 5 said selector into engagement with said lever, a common control member for both of said movements, and means to operate said needles and the loop-forming means cooperating therewith and likewise controlled by said control member. 10

ALFRED GRAENZ.
